Int. Cl. D12—16

U.S. Cl. D54—1 R

FIG. 2.

FIG. 3.

FIG. 1 is a perspective view of the front and one end from above of an extruded member for the sliding roof of a vehicle, showing my new design;

FIG. 2 is a cross-sectional view thereof taken along line 2—2 in FIG. 1; and

FIG. 3 is a rear elevational view thereof.

The extruded member is of constant cross section throughout and has been broken away at the center in FIGS. 1 and 3 to indicate indeterminate length.

I claim:

The ornamental design for an extruded member for the sliding roof of a vehicle, as shown and described.
